UNITED STATES PATENT OFFICE.

WALTER P. KILNER, OF BUFFALO, NEW YORK.

RUBBER BOOT.

1,174,166.

Specification of Letters Patent.

Patented Mar. 7, 1916.

Application filed June 19, 1915. Serial No. 35,089.

To all whom it may concern:

Be it known that I, WALTER P. KILNER, a citizen of the United States, residing at Buffalo, in the county of Erie and State of New York, have invented certain new and useful Improvements in Rubber Boots, of which the following is a specification.

This invention relates to new and useful improvements in rubber boots, and pertains 10 more particularly to that type of boot having an extension to receive the upper portion of the wearer's limb, and known as hip boots.

It is well known by wearers of this type 15 of boot that even though the extension of the boot be folded down, the boots when left standing will crush down or fall over, thus necessitating considerable preparation of the boot before the foot can be inserted 20 therein. Furthermore in boots of this type when the extended portion is folded down around the upper of the boot, it will not stay of its own accord owing to the movements of the boot upper during the operation 25 of walking. Furthermore, the creases and folds which occur in the ordinary boot when walking cause the upper to crack and crease owing to there being no means provided to return the upper to its normal 30 position.

It is the object of the present invention 35 to obviate all of the above disadvantages known to rubber boots of the hip type, and at the same time produce an article as cheaply as at the present time.

Referring to the drawings, Figure 1 is a 40 perspective view of a boot showing the invention removably secured in the upper portion thereof; Fig. 2 is a perspective view 45 of a boot showing a modified form of the invention in which the device is permanently secured in the top of the boot; and Fig. 3 is a perspective view partly broken away of the device.

Referring more specifically to the drawings, the reference character 1 designates 45 a rubber boot and 2 the upper limb extension thereof which as shown in the draw-

ings is folded down over the upper proper of the boot.

A resilient metal band 3 is inserted on the interior of the boot at the ton of the upper thereof and at the point of juncture of the upper and the hip extension, said resilient metal band being frictionally retained within the boot. As shown in Fig. 3 a fabric covering 4 incloses the metallic band 3, said fabric covering being preferably secured to the resilient metallic band by means of cement or the like, but it is 55 to be understood that said covering may be secured to the metallic band in any desired manner.

In the modified form shown in Fig. 2 the 60 resilient metallic band 5 is placed upon the interior of the top of the boot before the upper edge of the lining has been secured, and with the said band in this position the upper edge 6 of the lining is folded around the metallic band and has its free end secured to the interior of the boot by means 65 of cement or the like.

By making the metallic band circular in 70 form it will be seen that the top of the boot upper is maintained in a circular position at all times which circular position of the upper reinforces the latter, and causes 75 said boot to stand in an upright position with the top of the upper at all times in readiness to receive the foot of a person 80 desiring to put the boot on, and regardless of the position of the hip extension 2.

Having thus described the invention what is claimed is:

In combination with a rubber boot having a hip extension secured to the open end of the upper, an unbroken resilient metal band of an outside diameter equal to the inner diameter of the upper, said resilient metal band being provided with a friction 85 increasing surface for retaining it in place 90 at the juncture of the upper with the hip section.

In testimony whereof I affix my signature.

WALTER P. KILNER.
